UNITED STATES PATENT OFFICE.

CARL O. NYGAARD, OF MINNEAPOLIS, MINNESOTA.

HOT-WATER FURNACE OR HEATER.

Application filed January 28, 1924. Serial No. 638,147.

This invention relates to a hot water heater or furnace and is applicable to furnish a supply of hot water steam or vapor wherever needed, particularly to the radiator in a hot water steam or vapor heating system.

It is an object of this invention to provide such a heater or furnace comprising superposed sections provided with gas and water passages to effect an efficient circulation of heated air and the products of combustion therethrough, as well as an efficient circulation of the water, steam or vapor.

It is a further object of the invention to provide such a device in which the superposed sections comprise hollow concentric rings connected by radially disposed hollow arms, the space between said rings and arms forming gas passages and said members having central passages therethrough communicating with said hollow arms, the hollow rings, arms and central passage forming water chambers.

It is still another object of the invention to have a heater or furnace composed of such superposed sections with gas passages therethrough, in combination with means at the top and bottom of the heater or furnace to regulate such gas passages.

These and other objects and advantages of the invention will more fully appear from the following description made in connection with the accompanying drawings in which like reference characters refer to the same parts throughout the different views, and in which,

Fig. 1 is a vertical section through the device taken substantially on the line 1—1 of Fig. 2;

Fig. 2 is a horizontal section taken on the line 2—2 of Fig. 1;

Fig. 3 is a plan view of one of the sections used, a part thereof being shown in horizontal section;

Fig. 4 is a section taken on the line 4—4 of Fig. 1;

Fig. 5 is a section taken on the line 5—5 of Fig. 1, the same being shown on a reduced scale; and

Fig. 6 is a vertical section on a somewhat enlarged scale of one of the connecting sleeves used.

Referring to the drawings, the device comprises a hollow or shell-like frusto-conical base frame 1, having concentric ribs 1^a and 1^b at its top provided with annular grooves therein. A flange 1^c extends between the

bottom of the ribs 1^a and 1^b which is provided with circumferentially spaced apertures 1^d. An annular plate 2 rests upon the flange 1^c and is adapted to be rotated between the ribs 1^a and 1^b and on said flange, which plate is provided with a laterally projecting handle 2^a which projects through a slot in the outer rib 1^a by means of which handle the plate 2 is rotated. Plate 2 is also provided with circumferentially spaced openings 2^b which may be brought into or out of alignment with the opening 1^d in the flange 1^c. Supported upon the ribs 1^a and 1^b are a plurality of superposed circular sections 3, one of which is shown in plan in Fig. 3. The sections 3 are of considerable vertical extent and have co-operating annular tongues and grooves on their respective horizontal sides, so that the sections fit together in superposed relation, as clearly shown in Fig. 1. Said sections 3 comprise spaced hollow rings 3^a and 3^b which are connected by radially extending hollow arms 3^c and 3^d, respectively. The spaces between the rings 3^a and 3^b and the arms 3^c and 3^d form vertical openings 4 and 5 through the sections 3 and other vertical passages 3^e are formed through said sections, being surrounded with suitable walls extending between the top and bottom of said section. The sections 3 also have a central passage therethrough preferably of cylindrical shape, as illustrated, with which the inner ends of the hollow arms 3^c communicate, the open inner ends of said arms forming vertical slots 3^f, as shown in Figs. 1 and 3. The various members or sections 3 are arranged in said superposed relation with the openings 3^e, 4 and 5 in vertical alinement, so that vertical passages are formed extending from the lower section 3 to the top section 3, as shown in Fig. 1. The central passage of the lowest section 3 is closed, as shown at 6 and it will be seen that the plate 2 and flange 1^c are disposed directly below the vertical passages formed by the openings 3^e and 5. The top section 7 rests upon the uppermost section 3, being provided in its lower side with concentric tongues fitting in the concentric grooves in said uppermost section 3 and said section 7 is provided with a central chamber 7^b, the top of which is closed and said chamber is connected by radial arms 7^c to an outer ring 7^d, which ring 7^d has vertical gas passages 7^e therethrough similar to and aligned with the gas

passages 3^a. Circumferentially spaced gas passages are thus formed between the ring 7^a to the chamber 7^b and the arms 7^c. An annular flange 7^a upstands from the top of chamber 7^b and an annular plate 8 rests upon the top of section 7 having a central opening fitting about the flange 7^a, which plate is thus rotatable on section 7 and about said flange. The plate 8 is provided with circumferentially spaced sector-shaped openings 8^a adapted to be brought into or out of alignment with the openings between the arms 7^c and said plate is provided with an operating handle 8^b projecting through a slot in an upwardly projecting rib 7^c extending around the upper and outer edge of section 7. A top dome-shaped member 9 has an annular tongue at its bottom edge adapted to fit in the groove in rib 7^c, the outer surface of said top being flush with the outer surface of section 7 and the sections 3. The top 9 is contracted at its upper central portion to form a conduit adapted to be connected to the chimney. An inlet pipe 10 for water is connected to the outer wall of the lowermost section 3 and an outlet pipe 11 for water is connected to the outer wall of the section 7.

An intermediate section 13 is provided similar in all respects, to the sections 3, except that it does not have the openings 3^c into the central passage thereof and inlet and outlet pipes 14 and 15, respectively, connect with the outer wall of said section 13 at opposite sides thereof. The sections 3, 7 and 13 are connected at their central portions by sleeves 16 which project at their ends some distance into the adjacent central portions of the said sections. The sleeves 16 are slightly tapered at their ends, as shown at 16^a in Fig. 6 and are driven into the central portions of the various sections so that the sections are connected and a continuous passage is formed centrally thereof from the bottom wall 6 to the top of chamber 7^b. A burner 17 for gas, oil or other suitable fuel is disposed immediately below the center of the lowermost section 3 and its wall 6. Said burner will be supplied with fuel by conduit 18 adapted to be connected to a suitable fuel supply.

In operation, the inlet and outlet pipes 10 and 11 will be connected to the device to which the heated water is supplied, such as the radiators of a hot water system and said inlet pipe 10 will also be connected to a water supply system not shown. Water will enter pipe 10 and flow into the outermost ring of the lowermost section 3 around the passages 3^a therethrough, will pass through the arms 3^c into ring 3^b and through arms 3^c, slots 3^c into the central chamber of the section. Said water will rise through the central chamber and flow out through the slots 3^c of the next section into the various

water chambers therein. The water chambers of all of the sections will thus be filled. The burner 17 being lighted and the plates 2 and 8 being turned to close the passages through flange 1^c and between arms 7^c, the heated air and products of combustion will pass upwardly through the aligned space 4 of the sections, as indicated by the lower arrows in Fig. 1, and this air will then pass downwardly through the passage 7^c formed by the aligned openings 5 and will then return, as indicated by the outer lower arrows in Fig. 1, up through the passage formed by the aligned openings 3^c, said heated air and products of combustion then being considerably cooled in passing out through the top of the member 9. The water in the various sections will thus be heated and will rise through the various sections through the central passages thereof through the slots 3^c so that the heated water will pass out of the outlet 11 to the radiators. The returning cooled water will return through inlet pipe 10 to again circulate through the device. It will be understood, of course, that the connection to the water supply will be turned off as soon as the heater is suitably supplied with water. When a strong draft is desired, as when starting a fire, one or both of the plates 2 and 8 may be revolved to bring the openings therein in register with the openings through the flange 1^c or between the arms 7^c, respectively, so that a free passage for the air and products of combustion will then be effected directly through the various aligned gas passages 4, 5 and 3^c. After the fire is well under way and the furnace or heater brought to the proper temperature, the gas passages may be controlled as desired by rotating the plates 2 and 8.

It will be noted that the section 13 is not connected into the circulating system by the slots 3^c. This section is provided to furnish a supply of hot water for the purpose of household and domestic use. It is desired to have this water clean at all times and the inlet and outlet pipes 14 and 15, respectively, will be connected in a domestic water supply line so that hot water may be drawn from section 13 through the pipe 15 when desired, said hot water being replaced by water running through the pipe 14.

From the above description it is seen that applicant has provided a simple and efficient hot water heater or furnace. The same can readily be constructed of the superposed sections which are easily and inexpensively made as integral castings, it merely being necessary to connect the sections by the sleeves 16 and make the necessary water connections. The water is efficiently heated and circulated and the heat from the products of combustion is efficiently used.

It will, of course, be understood, that various changes may be made in the form, details, arrangement and proportions of the parts without departing from the scope 5 of applicant's invention, which, generally stated, consists in a device capable of carrying out the objects above set forth, such as shown and described and set forth in the appended claims.

10. What is claimed is:

1. A hot water heater comprising a series of superposed circular sections, a series of concentric gas passages therein extending vertically in alinement through said sections, a series of concentric water chambers formed in said sections between said gas passages, radial arms connecting adjacent chambers, a central cylindrical water chamber communicating with said first mentioned chambers, a burner below said sections, said gas passages being normally adapted to communicate directly from above said burner to an upper outlet, and means for closing certain of said gas passages to compel air and products of combustion from said burner to serpentine from one set of the concentric gas passages to the next adjacent set of concentric gas passages to reach a final outlet.
2. A hot water heater comprising a series of superposed sections, concentric alined gas passages therein running vertically through said sections, concentric water chambers formed in said sections by said gas passages, radial arms communicating between said water chambers and communicating gas passages above the upper section and below the lower section connecting the inner concentric gas passages to the outer gas passages at the top and bottom of the superposed structure, and means for closing said communicating gas passages to direct air and other products of combustion alternately upward and downward through successive concentric gas passages to pass tortuously to an outlet.
3. A hot water heater comprising a series of superposed sections having a plurality of radially and circumferentially spaced gas passages therethrough, a space between said gas passages forming water chambers, said gas passages being arranged to form unobstructed radial passages from the outer wall to the inner wall of said section, said section having central cylindrical openings therethrough, the walls of which have circumferentially spaced slots alined with said unobstructed passages, said central passage being closed at the lower side of the lowermost section, a burner disposed below said lowermost section, and means for compelling a return circulation of gases heated by said burner through the adjacent outwardly spaced gas passages.
4. A hot water heater comprising a series of superposed sections having radially and circumferentially spaced gas passages therethrough, the space between said gas passages forming water chambers, said gas passages being arranged to form unobstructed radial passages from the outer wall to the inner wall of said sections, said sections having central cylindrical openings therethrough, the walls of which have circumferentially spaced slots alined with said unobstructed passages, said central passage being closed at the lower side of the lowermost section, a burner disposed below said lowermost section, means for closing or partly closing the outer gas passages through said lower section, the central water chamber of the uppermost section being closed at its top, and means for closing or partially closing the inner gas passages through the uppermost section to compel air heated by said burner to move tortuously from inner to outer radially spaced air passages to an outlet at the top of such outer air passages.
5. A hot water heater comprising a series of superposed circular sections having a plurality of radially and circumferentially spaced vertically aligned gas passages extending therethrough at each side of the center thereof forming continuous passages from the bottom to the top of the heater, the space between said gas passages in said sections forming communicating water chambers, said sections also having central passages therethrough communicating with said water chambers, a burner disposed below the lowermost section, means disposed below the lowermost section for closing or partially closing certain of the outer gas passages therethrough, and means disposed above the uppermost section for closing or partially closing certain of the inner gas passages therethrough, whereby a return circulation of the gases of combustion from the top to the bottom of said gas passages may be obtained from inner to outer passages.
6. A hot water heater comprising a series of superposed circular sections, concentric water chambers therein, communicating arms between said chambers, vertically alined inner and outer gas passages extending vertically through the length of the superposed structure through adjacent concentric chambers, a damper for closing the outer gas passages at the bottom section, a damper for closing the inner gas passages at the top section, and a burner below said sections whereby when the said dampers are closed, the gases heated by said burner will pass first through the inner gas passages and then through the outer gas passages.

In testimony whereof I affix my signature.

CARL O. NYGAARD.
